CARL HERRMAN EIFFLER, OF NEW YORK, N. Y.

Letters Patent No. 71,721, dated December 3, 1867.

IMPROVEMENT IN LOCKING-KNOB LATCHES.

The Schedule referred to in these Letters Patent and making part of the same.

TO ALL WHOM IT MAY CONCERN:

Be it known that I, CARL HERRMAN EIFFLER, of the city of New York, 209, Bowery, in the county and State of New York, have invented a new and useful Improvement in Locks; and do hereby declare that the following is a full, clear, and exact description of this invention, which will enable those skilled in the art to make and use the same, reference being had to the accompanying drawing, forming part of this specification, in which drawing—

Figure 1 represents a horizontal section of this invention when applied to a door.

Figure 2 is a face view of the locking-mechanism in the door-knob when the knob is in gear with the latch.

Figure 3 is a similar view of the same when the knob is out of gear with the latch.

Figure 4 is a detached face view of the slotted disk for setting the locking-mechanism in the knob.

Figure 5 is a detached face view of the washer under the door-knob.

Similar letters indicate corresponding parts.

This invention relates to an improvement in locks of that class which are generally used on the front doors of dwelling-houses, and in which the latch is operated by two knobs, one on the outside and the other on the inside of the door, the outside knob being constructed in such a manner that it can be thrown in or out of gear with the latch.

My invention consists, first, in the arrangement of an adjustable screw in the end of the spindle, in such a manner that, by said screw, the length of the spindle and the position of the knob can be regulated to suit the thickness of the door; second, in enclosing in the knob the mechanism which serves to throw said knob in and out of gear with the latch; third, in the arrangement of a nut on the spindle, in combination with a movable stump and tumblers, in such a manner that, when the tumblers are set and the stump made to drop into the notches thereof, the knob is thrown in gear with the latch, and the door can be opened from the outside, but if the stump is withdrawn the knob turns freely on the spindle without having any effect on the latch; fourth, in the arrangement of a safety-stop, in combination with the knob and washer which form the socket for said knob, and with the tumblers contained in the knob, in such a manner that, when said tumblers and the knob are brought in the required position, the stop can be made to lock the outer knob, and prevent it from being turned, while the inner knob continues to act on the latch; fifth, in the arrangement of a disk with cam-slots, in combination with the movable stump with the stop and tumblers, in such a manner that, by turning said disk, the stop and stump can be thrown simultaneously out of or in gear with the tumblers, provided said tumblers have been brought in the required position; sixth, in the arrangement of an abutment between the key-hole and safety-stop, in such a manner that said stop cannot be reached and its position disturbed by an instrument introduced through the key-hole.

A represents a case, made of cast iron, or any other suitable material capable of forming the guide and protection of the latch B, and of the ordinary locking-mechanism, if such is to be applied. The latch B is operated by means of the spindle C, which extends through the door to which the lock is attached. To the inner end of this spindle is secured the knob D, and to its outer end the knob E, and, in order to adjust the spindle to suit the thickness of the door, it is provided with a screw, *a*, the head of which may be square or round, said screw being secured in the spindle in the direction of its axis. Through the head of the screw *a*, a hole is bored, which is tapped to receive the set-screw *b*. By these means the length of the spindle C or the distance between the two knobs, D E, can be regulated with the greatest nicety, so that, in pulling one of the knobs, the spindle will have no longitudinal motion, while said knobs will not interfere with the revolving motion of the spindle.

The outer end of the spindle C extends into the knob E, which is provided with a mechanism, by means of which it can be thrown in or out of gear with said spindle and with the latch. This mechanism consists principally of a nut, *c*, which is provided with one or more projections, and which is secured on the spindle C, so that it cannot revolve independent of the same. This nut acts on a movable stump, *d*, the position of which is governed by a cam-slot, *e*, in the disk *f*, and by tumblers *g*, which turn freely on the outer end of the spindle. If these tumblers are adjusted to the position shown in fig. 2, all their notches, *h*, register, and the stump *d* is permitted to enter and to approach the centre of the spindle C, close enough to allow it to come in contact with the projection or projections of the nut *c*, in whatever direction the knob may be revolved.

The position of the tumblers *g* is regulated by the key *k*, which is composed of a piece of sheet metal, provided with notches at its ends, and which is introduced through a slit in the circumference of the knob. Said tumblers hang loosely on the outer end of the spindle and they are provided with notches *h* to receive the stump, and with notches *j* to receive the head of the safety-stop *l*. This stop swings on a pivot, *m*, secured in the shank of the knob *E*, as shown in fig. 1, so that, by turning it on its pivot to the position shown in said figure, the head can be made to engage with the notches *j* in the tumblers, (provided the tumblers are properly set,) and, by swinging it back in the direction of the arrow marked on it in fig. 1, its head releases the tumblers, and its tail end catches in a notch, *o*, in the washer *F*, which is situated between the knob *E* and the door. This latter motion of the safety-stop, however, can only take place when the knob is brought in the proper relation to the washer, said relation being indicated either by centre-points or by other suitable marks. The washer *F* is firmly secured to the door, and, if the safety-stop is made to drop into the notch *o*, the knob *E* is firmly retained in position and prevented from being turned, whatever the position of the stump *d* may be. In this position the door cannot be opened from the outside, until, by introducing the key, the tumblers are brought in such a position that their notches *h* and *j* will admit the stump *d* and the head of the safety-stop *l*. After the tumblers have been thus adjusted, the stump and stop are forced into the notches of the tumblers by the action of a disk, *f*, (see fig. 4,) which is provided with cam-slots *e e'* and with a button, *r*, and which revolves in the hollow body of the knob, its motion being limited by the segmental recess *s*, in which the button *r* moves. If this button occupies the position shown in fig. 2, the stump *d* has entered the notch *h*, and the tail end of the safety-stop has left the notch *o* in the washer, and the knob *E* is thrown in gear with the spindle and latch by the action of the nut *c* on the stump *d*. If the mechanism is in this position, and the knob is turned, the tail end of the stop *o* moves in the annular recess *t* in the washer *F*. (See fig. 5.) If the knob *E* is thrown out of gear with the latch and locked by the safety-stop, the door cannot be opened from the outside, while the inner knob remains in gear with and operates on the latch as usual.

That portion of the spindle *C* next to the outer surface of the door is made round, so that if the washer *F* should be forced off from the door, said spindle cannot be readily grasped by a wrench or other instrument with sufficient tenacity to throw the latch back and to open the door. The safety-stop *o* is also protected by an abutment, *u*, which prevents its being reached and thrown out of position by an instrument introduced through the key-hole.

By this arrangement a latch is obtained which cannot be picked, and which can be readily changed from one door to another.

What I claim as new, and desire to secure by Letters Patent, is—

1. The arrangement of an adjusting-screw, *a*, provided with a transverse hole to receive the set-screw *b*, in combination with the spindle *C* and knobs *D E*, constructed and operating substantially as and for the purpose set forth.
2. Enclosing in the knob *E* the mechanism which serves to throw said knob in and out of gear with the latch, substantially as and for the purpose set forth.
3. The nut *c* on the spindle *C*, in combination with the movable stump *d*, tumblers *g*, knob *E*, and latch *B*, constructed and operating substantially as and for the purpose set forth.
4. The safety-stop *o*, in combination with the knob *E*, washer *F*, and latch *B*, constructed and operating substantially as and for the purpose described.
5. The disk *f* provided with cam-slots *e e'*, in combination with the movable stump *d*, safety-stop *o*, and tumblers *g*, constructed and operating substantially as and for the purpose set forth.
6. The abutment *u*, in combination with the key-hole and with the safety-stop *o*, constructed and operating substantially as and for the purpose described.
